CLAIM

The ornamental design for a ring and display stand set, as shown and described.

DESCRIPTION

FIG. 1 is an exploded top and front perspective view of a ring and display stand set showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top front perspective view thereof, shown in an assembled position.

The dash-dash broken lines in the drawings represent portions of the ring and display stand set and form no part of the claimed design. The dot-dash broken lines in FIGS. 1, 2, 6 and 8 represent a claim boundary and form no part of the claimed design.

1 Claim, 4 Drawing Sheets
